19 Claims. (Cl. 311—6)

1

This invention relates to tables for X-ray examination purposes.

One of the principal objects of the invention is to provide an X-ray table which can be quickly and easily tilted to any desired angular position from the vertical through the horizontal and into a wide range of Trendelenburg positions without increasing the height of the table from the floor when in horizontal position.

Another object is to provide a tilttable X-ray table which does not require counter weights for balance, and which can accordingly be of stronger and more rigid construction than in previous tilttable fluoroscopic tables without an over-all increase in weight.

It is also an object of the invention to provide a tilttable X-ray table which is so constructed and mounted that the area available for fluoroscopy is substantially longer and wider than in previous tables but without increasing the over-all dimensions of the table or the floor space occupied thereby.

A further object of the invention is to provide a tilttable X-ray table which is supported for tilting movement about a horizontal axis wherein this tilting axis of the table is movable in a vertical plane during tilting movement of the table, being raised when the table tilts in either direction from the horizontal and lowered when the table tilts toward the horizontal.

A still further object is to provide an X-ray table having an improved top construction adapted for the ready securing thereto of attachments such as head and foot rests without the use of slots, studs or like irregularities on the top surface such as might tear the clothing or skin of a patient.

Other objects and advantages of the invention will be apparent from the following description, the accompanying drawings and the appended claims.

In the drawings, which illustrate a preferred embodiment of the invention, and in which like characters of reference designate like parts throughout—

Fig. 1 is a view in perspective illustrating a tilttable X-ray table constructed in accordance with the invention and shown in horizontal position;

Fig. 2 is a view in elevation of the foot end of the table shown in Fig. 1;

Fig. 3 is a front elevational view of the table shown in Fig. 1, with the table tilted to a 40° Trendelenburg position;

Fig. 4 is a view similar to Fig. 3 showing the table tilted to vertical position;

Fig. 5 is a somewhat diagrammatic view in front elevation illustrating the course followed by points on the table in tilting from the horizontal to the positions shown in Figs. 3 and 4;

2

Fig. 6 is an enlarged view taken approximately on the line 6—6 in Fig. 2 showing the inside of the rear leg of the table;

Fig. 7 is an enlarged view in vertical section through the front leg and adjacent portion of the table, the view being taken approximately on the line 7—7 in Fig. 5;

Fig. 8 is a detailed view in transverse section through the top edges of the table showing one means for mounting an attachment such as a head rest in accordance with the invention;

Fig. 9 is a view similar to Fig. 8 showing another form of attachment in accordance with the invention;

Fig. 10 is a detail view of the attaching mechanism shown in Fig. 9, the view being taken approximately on the line 10—10 in Fig. 9; and

Fig. 11 is a detail view of a portion of the attaching mechanism shown in Figs. 9 and 10.

The present invention provides a tilttable X-ray table mounted for tilting movement about a single axis relative to the table and capable of tilting movement from horizontal to vertical and also from horizontal through a wide angular range of Trendelenburg positions. At the same time, the table of the invention when in the horizontal position is no higher than the conventional table height for convenient use by an examining physician. This result is accomplished in accordance with the invention by raising the tilting axis as the table tilts in either direction from the horizontal.

Also, the invention makes it possible to pivot the table substantially on its center of gravity, thus not only reducing the force necessary to bring about the desired tilting movement but also permitting the elimination of counterweights.

Another result of the invention is to increase the effective surface area of the table top without increasing its overall dimensions as compared with previous tilttable X-ray tables, and the invention provides also for similarly increasing the depth of the table without impeding its tilting operation, thus permitting the X-ray tube to be spaced farther from the table top, which is a highly desirable operational feature since it permits the use of X-rays of higher power without danger to the patient and thus makes for clearer vision during fluoroscopy and for clearer X-ray pictures when the table is used for radiography.

Also since the image-forming rays diverge to a lesser extent when the tube is farther from the table top, there is improved freedom from distortion of the image.

In accordance with the invention, the slots, studs or other irregularities conventionally provided along the edges of the table top for mounting attachments such as head and foot rests may be eliminated, and provision for such attachments is made along the edges of the table.

below its working top, thus further increasing the useful surface area and also insuring against injury to the skin or clothing of a patient or like undesirable results. Also, this provides a smooth and easily cleaned top surface for the table and eliminates the possibility of unsanitary conditions arising from notches or slots in the table top.

In the preferred embodiment of the invention shown in the drawings, the fluoroscopic table is provided with a top panel 20 of Bakelite or other satisfactory material suitably permeable to X-rays, and the head and foot ends of the table are designated generally by the reference characters 22 and 23 respectively. A cable 24 is shown as leading from head end 22 to a suitable source of electric power for the X-ray tube within the table. A fluoroscopic screen indicated generally by the reference character 25, and which may be of conventional construction, is shown as attached to the table by a suitable mounting mechanism 26 providing for free adjustment of the screen vertically and laterally of the table and for free swiveling movement, and also preferably permitting the screen to be swung out of line with the table to allow free access by a patient to the table top.

The supporting base for the table is shown as comprising a front leg 30 and rear leg 31 of generally complementary construction secured together by means of connecting rods 32 and nuts 33. As shown in detail in Fig. 6, the interior of each table leg is provided with reinforcing ribs 34 and reinforcing bosses 35 which receive the connecting rods 32. The table is pivotally secured to the upper end of each of a pair of slide members 40, one of which is mounted for vertical sliding movement in each of legs 30 and 31 by means of U-shaped bearing members 41 of brass or other suitable material bolted or otherwise secured to the inner surface of the table leg. As shown, each of slide members 40 has a stud bolt 42 at its upper end which fastens directly to an upper portion 43 of the frame of the table, spacer sleeves 44 being provided to maintain the table in properly spaced relation from the slide members. Bolts 42 are so connected to the table that their axes 45 will coincide and will pass through approximately the center of gravity of the table, thus providing for tilting movement of the table with minimum effort and eliminating the necessity for counterweights such as must be used in the case of fluoroscopic tables mounted for tilting movement about an axis removed from the center of gravity.

The mechanism for imparting tilting movement to the table includes a pair of substantially identical gear tracks 50, one for each side of the table, which are roughly L-shaped in cross-section, as shown in Fig. 7, and include an outer toothed portion 51 and a smooth track portion 52. Each of these tracks 50 may be bolted or otherwise secured to a reinforcing plate or panel 53 which is in turn bolted, riveted or otherwise secured to the side of the table and frame portions 43, thus providing a simple but strong construction without materially affecting the overall weight or width of the table. As is shown particularly in Fig. 5, each of tracks 50 has an arcuate outline resembling the letter W and is composed of three segments of circles each having its center spaced longitudinally of the table from the pivotal axis 45. The two outer segments are shown as being of the same radius and with their respective centers 55 and 56 lying in

5 a plane which is parallel to the table top 20 and spaced between the table top and the track and slightly above pivot axis 45. The intermediate segment is of substantially shorter radius than the outer segments and is curved in the opposite direction, with its center 57 lying substantially below the table top.

10 A motor 60 for actuating the tilting mechanism of the table is shown as positioned adjacent the rear table leg 31, where it will be out of the way of a physician standing in front of the table, and is secured in driving connection with a shaft 61 which extends across to front leg 30. Satisfactory results have been obtained by 15 utilizing as motor 60 a gear head electric motor, and in order to facilitate tilting during observation of a patient—as is desirable under some conditions such as in connection with spinal injections—suitable switch controls for the motor may be provided at a plurality of convenient locations such, for example, as at 58 on the front table leg and at 59 on the frame of fluorescent screen 25. Also, these switches will preferably be so constructed and connected that they may be actuated to cause the motor to drive in either direction at the will of the examining physician, and the motor should be provided with automatic braking means effective to prevent its rotation in either direction except when power is applied.

20 The drive shaft 61 carries a pair of drive gears 62, one adjacent each table leg, which are in driving connection through a gear train 63 and 64 with a driven gear 65. Gear 65 is keyed to a bushing 66 journaled on a stud member 67 supported by the table leg as shown in Fig. 7. This 25 gearing is duplicated at the front and back of the table, thus providing for balanced support of the table and balanced drive for tilting movement, and the studs 67 serve in use to support most of the weight of the table. They are accordingly 30 made of appropriate thickness and strength, and each is provided, as shown, with a suitable supporting boss 68 formed on the table legs. Gears 35 63 and 64 may be rotatably supported on similar 40 studs or bolts mounted in similar bosses 69 on the table leg.

45 A gear 70, which may be of the same diameter and number of teeth as gear 65, is keyed to bushing 66 for rotation with gear 65, the bushing thus serving to transmit directly to gear 70 the driving force from drive gears 62 and the motor 60. This gear 70 meshes with the teeth 51 on track 50, and a relatively large ball bearing 71 is mounted on stud 67 adjacent gear 70 and is 50 adapted to engage and support the smooth portion 52 of track 50 and thus to take the main weight of the table off gears 70 to avoid undue load on the gear teeth 51 and the teeth of gears 70. A crank arm 72 is journaled on each bushing 66 and has pivotally secured to its outer end a roller or bearing 73 adapted to engage and ride on the upper edge of each track 50. Roller 73 is shown as secured to arm 72 by means of a bolt 74, and the radius of roller 73 and the distance between its axis and the axis of stud 67 55 are so chosen that gear 70 will at all times be held in meshed relation with the teeth 51 on track 50 in all angular positions of the table. A spacer 75 is shown in between gear 65 and crank 70, which may be a separate washer or a collar formed on gear 65. During tilting motion of the table, as described hereinafter, these arms 72 will oscillate about the studs 67 to follow tracks 50 as they tilt and insure proper driving of the table. The off-set construction of gears 70 with respect

to the remainder of the gearing is to provide clearance for tracks 50 since there might otherwise be contact between the tracks and the gear train if the latter were in the same plane as the tracks. In Fig. 1, this operating mechanism is shown as concealed by a shield 77, but this shield is omitted in the other views for greater clarity.

The operation of the above mechanism for tilting the table is illustrated particularly in Figs. 3 to 5. The usual position of the table for purposes of general examination is horizontal, and in this position the gears 78 are in engagement with the intermediate segments of the gear tracks 50, as shown in Fig. 5, with slide members 40 and the pivotal axis 45 of the table at their lowest positions with respect to the table legs. The only part of this system which remains fixed with relation to the legs in all positions of the table is the axis of rotation of gears 78, which is the axis of studs 67. All other portions of the table change their position in space with respect to the table legs as the table tilts, the pivotal axis 45 rising vertically with slide members 40, and all the other parts of the table pivoting about this axis 45. Also, since the axis of gears 78 is spaced laterally from and below table axis 45, and since the table axis is selected to coincide with the center of gravity of the table, as described, the reacting force exerted by studs 67 must be such that its vertical component is the weight of the table and its horizontal component is opposed by the reaction on table axis 45 exerted by the slide members 40 and the guide bearings 41.

When it is desired to tilt the table from the horizontal to the vertical or an intermediate angular position, motor 60 is actuated to rotate shaft 61 and gears 62 clockwise as viewed in Fig. 5, which will cause gears 78 to rotate counter-clockwise and to apply a torque to gear tracks 54. This torque will be translated into motion of the gear tracks and hence of the table itself, and since the table axis is limited to vertical movement and by reason of the arcuate shape of each gear segment adjacent the foot end of the table, the table will ride up with this gear segment. At the same time, the torque applied to the segments will be translated into vertical movement of table axis 45 and the slide members 40, but since the gear tracks are held in contact with gears 78 through the action of crank arms 72 and rollers 73, the table will be forced to tilt about its axis 45 towards the vertical position shown in Fig. 4. If the position of axis 45 is so chosen that its distance from the foot end of the table is less than the sum of its height from the floor when the table is horizontal plus its vertical travel as described, the table can swing through a complete quarter-circle to a 90° vertical position, and this position is shown in full lines in Fig. 4 and is indicated in dotted lines in Fig. 5.

Tilting of the table to a Trendelenburg position is accomplished by reversing the direction of rotation of motor 60 and gears 78, and the action is substantially the converse of the tilting operation just described. During the return movement of the table from the vertical to the horizontal position, the tracks 50 will move in the direction of the foot end of the table and the table axis 45 will descend to its position shown in Fig. 5. Thereafter the gear segments of tracks 50 adjacent the head end of the table will come into engagement with gears 78, and the table will be caused to ride up again with axis 45 and slide members 40 and at the same time to tilt into a Trendelenburg position. If the

position of table axis 45 is chosen as described in connection with the movement to a vertical position, the illustrated construction permits the table to tilt through a range of Trendelenburg positions as high as about 40° without danger of the head end of the table striking the floor. Also, even with this considerable increase in the range of available Trendelenburg positions over conventional tilttable tables, the above construction permits deepening the table sufficiently to position the tube within the table as far as 16 inches from the table top, which as already noted provides for the use of X-rays of higher power to give clearer fluoroscopic and radiographic images without danger to the patient, and it also provides adequate clearance within the table for a high voltage tube.

The above motions of the table will be readily visualized by reference to Fig. 5, which illustrates a series of positions occupied by the ends of the table during its full tilting movement between the limit positions shown in Figs. 3 and 4. Fig. 5 clearly shows that with the exception of table axis 45, which follows a straight vertical path, all other points on the table follow curving paths of different shapes. For example, the points A and B at the head and foot ends of the table follow more or less complementary paths of a shape resembling an involute curve. The point C, which is a point at the top of the table from which a normal to the table top will pass through table axis 45, follows a curve composed of two seemingly unrelated sections. The paths followed by other points may readily be plotted by reference to the paths of the two ends of the table. It should also be noted that the supporting axis of the table—i. e., the axis which in any given position of the table coincides with the axis of gears 78—may be considered as having relative movement with respect to the table along a path corresponding with the shape of tracks 50.

The invention provides for readily stopping the table in any desired angular position intermediate its limit positions shown in Figs. 3 and 4 by simply shutting off motor 60, the motor brake being automatically applied as soon as the motor is stopped. In order to facilitate selection of a particular angular position, a scale 80 may be secured to the front of the table, as shown in Fig. 1, and a cooperating pointer 81 suitably fixed to the front slide member 40 to indicate the angular movement of the table with respect to the horizontal. Switch means may also be provided for automatically stopping the table at its limit positions and also at the horizontal position, the latter being useful to relieve the examining physician from having to use scale 80 to determine when the table is precisely horizontal. Satisfactory results have been obtained utilizing micro-switches for this purpose, and Fig. 5 illustrates diagrammatically a suitable positioning of these switches.

As shown, three such switches are indicated at 90, 91 and 92, and they may be suitably secured, for example, to the rear table leg 31 and connected in the circuits to motor 60. Switch 90 is provided with a cooperating pin or contact member 95 carried by the table, and their relative positionings are so calculated that this pin 95 will contact switch 90 to shut off motor 60 whenever the table reaches a precise horizontal position from either a Trendelenburg position or a vertical position. If it is desired then to continue the tilting movement beyond the horizon-

tal, the main control switches for the motor may be actuated to start the motor again. Switch 91 is set to stop tilting motion of the table when it reaches its maximum Trendelenburg position, and a pin or contact member 96 is secured to the table in such position that it will come into contact with the switch when the table reaches the limiting Trendelenburg position as shown in Fig. 3. Switch 92 is designed to stop tilting motion of the table when it reaches the 90° vertical position, and a pin or screw 97 is secured adjacent the foot end of the table in such position as to bring about the desired operating contact with switch 92 as shown in Fig. 4.

The above motions of the table are smooth and easily controlled, and the table may be quickly and readily adjusted to any desired angular position or series of angular positions in accordance with the desires of the examining physician. When the table axis 45 is selected to coincide with the center of gravity of the table, as described, the tilting movement requires substantially no more force than is needed to raise the weight of the table through the required vertical distance for the pivot axis, and it is unnecessary to use counterweights such as are conventionally employed in tiltable X-ray tables mounted for movement about a stationary pivot positioned closer to the foot end of the table than is the case with the present invention. This in turn provides for substantial lightening of the table and thus permits the use of a simpler and stronger frame without increasing the overall weight of the table. Figs. 1, 7 and 8 illustrate details of this frame construction and show also one example of the improved and simple means for mounting attachments for the table top, such as a head or foot rest, in accordance with the invention.

The main frame for the table includes the side bars 43, to which the pivotal studs 42 are secured, and a second pair of side bars 100 which are connected with and spaced above the bars 43 to leave an opening 101 just below the table top in which a bucky and cassette carriage may be mounted for the usual movement longitudinally of the table for use in radiography. Such a carriage is indicated generally by the reference character 99 in Fig. 1, and it will be noted that owing to the elimination of the counterweights which are provided at the foot end of a conventional tiltable table, the opening 101 extends from the foot end substantially the entire length of the table, thus permitting the bucky to travel as close as to within 3 inches of the foot end of the table.

An angle iron 102 is bolted or otherwise secured to each bar 100, and includes a downwardly depending flange portion 103 spaced from bar 100. The upper surfaces of angle irons 102 support Bakelite top 26 which may be bolted or otherwise secured thereto as shown. The outer sides of angle irons 102 are provided with a series of spaced holes 105, and Figs. 1 and 8 illustrate the use of these holes in mounting an attachment for the table top. Fig. 1 shows at 110 a clamp device for the head of a patient, and Fig. 8 shows fragmentarily at 111 the outer ends of the bracket member which carries this head clamp. Each of these bracket ends in turn has bolted or otherwise secured thereto an angled strap member 112 adapted to overlap the sides of the table and provided with a suitable pad 113 of felt or the like to prevent injury to the Bakelite surface. One of strap members 112 is also provided with an inwardly projecting stud 114 which is adapted to engage

5 in one of holes 105 as shown in Fig. 8. The strap member 112 at the other end of bracket 111 is provided with a thumb screw 115 threadedly mounted in a suitable boss 116 on the strap member and similarly adapted to engage in a hole 105 of the strap 112 on that side of the table.

With this construction, the bracket may readily and quickly be attached in position on the table by hooking the stud 114 in the proper hole 105 at the front side of the table, bringing the bracket down into position on the table top, and then locking it into position by screwing the thumb screw 115 inwardly until it is completely engaged in the opposite hole 105 on the back side of the table. The attachment may be removed with equal ease by backing off the thumb screw 115 and then lifting that end of the bracket sufficiently to permit disengagement of stud 114 from its hole 105. It will be seen that by means of this construction the top surface of the table is kept completely smooth and free from any irregularities such as might scratch or injure the clothing or skin of a patient, particularly while getting on or off the table, while at the same time the attachments may be quickly and readily mounted in position whenever and wherever needed. The device illustrated in Fig. 8 is satisfactory for attachments such as head clamp or foot rest which includes a rigid bracket extending completely across the table.

Figs. 9 to 11 illustrate another type of mounting bracket useful in connection with attachments such as a compression band wherein the two ends of the device are not rigidly interconnected or where it is desired to make an attachment to one side only of the table. In this construction, each end 120 of the attachment is provided with an angled strap 121 generally similar in cross-section to the straps 112 but including a channeled flange 122 adapted to overlap and hook under the downwardly projecting flange 103 on angle 102. The outer surface of strap 121 carries a pair of brackets or ears 123 which provide a pivotal mounting for a hook 125 having an adjusting screw 126 threaded therein as shown in Fig. 11. A pair of screws 127, one on each side of hook 125, engage in slots 128 in brackets 123 as shown. With this construction the attachment may be secured to the table by simply hooking the channeled flange 122 under the flange 103 on angle 102. Hook 125 is then swung up until its hook portion is similarly engaged with flange 103, and the screw 126 is tightened to lock against the outer surface of flange 102. To remove the attachment, it is merely necessary to unscrew the adjusting screw 126, which permits the hook 125 to slide inwardly the length of slots 128 and thus to drop away from its hooked position. Thereafter the strap 121 may be readily unhooked from flange 103 and removed from the table. This type of attaching device is useful for an attachment such as a compression band, wherein two brackets are provided on opposite sides of the table and a cloth band is stretched therebetween.

65 The present invention accordingly provides an X-ray table having a variety of structural and operational advantages. The table is mounted for tilting movement in either direction from the horizontal about a single pivotal axis and is capable of tilting both to a 90° vertical position and to a 40° Trendelenburg position without changing the height of the table from the floor from a height found satisfactory for purposes of general examination. The tilting movement is accomplished smoothly and easily by means of a mo-

tor, and controls for this movement are provided at convenient locations for the examining physician. The construction of the table as described and illustrated also provides for increasing the useful area of the table top without increasing the overall dimensions or the floor area occupied by the table, and it also permits the use of stronger materials for the frame of the table without an overall increase in weight. This frame construction in turn provides for the use of attachments for the table top which are secured to the frame instead of to the table top and so affords great strength and rigidity without encroaching on the working area of the table top. The increased length of the table also provides adequate leg room for a patient to permit examination of the entire body without change of position.

The table of the present invention offers special advantages for use where floor space is at a premium, as for example in a doctor's office. When the table is used in the vertical position, the patient stands before the table top, and the examining physician must be substantially in line with the patient and table, thus requiring a considerable amount of floor space. With the present invention, as is clearly shown in Fig. 5, when the table is moved to the vertical position, there is substantial clearance between the vertical plane occupied by its top and the corresponding parallel plane occupied by its foot end when in the horizontal position. In Fig. 5 this clearance is represented by the horizontal distance between the vertical line A—B and the point B at the foot end 23 of the table in the horizontal position. It will accordingly be seen that the present invention reduces substantially to a minimum the over-all space requirements for effective operation of the table and permits its use even in a relatively small space such that when horizontal its foot end is closely adjacent a wall or other fixed object.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. X-ray apparatus comprising, in combination, a table for receiving the patient thereon, a supporting base for said table, means for pivoting said table about a transverse axis, means carried by said base providing a mounting for said pivot means movable with respect to said base in a substantially vertical plane, means carried by said base for supporting said table on an axis parallel to and spaced laterally from and below said pivotal axis, and means for causing a relative shifting of said supporting axis with respect to said table along a curved line including a segment of a circle having its center spaced from said pivotal axis to cause said pivot means to reciprocate and said table to tilt longitudinally about said pivotal axis.

2. X-ray apparatus comprising, in combination, a table for receiving the patient thereon, a supporting base for said table, means for pivoting said table about a transverse axis, means carried by said base providing a mounting for said pivot means movable with respect to said base in a substantially vertical plane substantially parallel to the width of said table, means carried by

said base for supporting said table on an axis spaced laterally from and below said pivotal axis, and means for causing a relative shifting of said supporting axis with respect to said table along a curved line including two segments of circles having their centers spaced longitudinally of said table on either side of said pivotal axis and lying in a plane between said segments and the top of said table and parallel to said table top, and including also a segment of a circle intermediate said first named segments and curved in the opposite direction therefrom, said relative shifting causing said pivot means to move vertically and said table to tilt longitudinally about said pivotal axis.

3. X-ray apparatus comprising, in combination, a table for receiving the patient thereon, a supporting base for said table, means for pivoting said table about a transverse axis, means carried by said base providing a mounting for said pivot means movable with respect to said base in a substantially vertical plane, a gear track secured to said table and including a segment of a circle having its center spaced from said pivotal axis, a gear wheel rotatably supported by said base and meshing with said gear track, and means for rotating said gear wheel to cause said pivot means to move vertically and said table to tilt longitudinally about said pivotal axis.

4. X-ray apparatus comprising, in combination, a table for receiving the patient thereon, a supporting base for said table, means for pivoting said table about a transverse axis, means carried by said base providing a mounting for said pivot means movable vertically with respect to said base, gear tracks secured to each side of said table and having gear teeth along the lower edges thereof, each of said tracks including two segments of circles having their centers spaced longitudinally of said table on either side of said pivotal axis and lying in a plane between said track and the top of said table and parallel to said table top, each of said tracks also including a segment of a circle intermediate said first named segments and having its center positioned on the opposite side of said track from the centers of said first named segments, each of said gear tracks meshing with a gear wheel rotatably supported by said base, motor means operatively connected with said gear wheels for rotation thereof in either direction to cause said table to tilt about said pivotal axis and said pivot means to move vertically, and means for maintaining engagement between each of said gear wheels and each of said gear tracks and comprising a roller engaging the upper edge of each of said tracks and rotatably carried by the outer end of a crank arm having its inner end mounted for rotation coaxially with said gear wheels.

5. X-ray apparatus comprising, in combination, a table for receiving the patient thereon, a supporting base for said table, pivot means forming a transverse tilting axis for said table located intermediate the ends thereof, means supporting said pivot means on said base for movement in an upwardly directed path with respect to said base, and cooperating drive means carried by said base and said table for effecting movement of said table about an axis eccentric with respect to said tilting axis and parallel thereto to cause tilting movement of said table about said tilting axis and simultaneous movement of said tilting axis along said upwardly directed path.

6. An adjustable X-ray table comprising a base, a table structure adapted to be mounted

11

on said base, means forming a pivot for said table located at an intermediate point lengthwise of said table, means on said base for supporting and guiding said pivot in a predetermined upward path of movement, and additional means on said base connected to said table along a curved arc having a center spaced from the axis of said pivot for concurrently rocking said table about said pivot and shifting said pivot along said path.

7. X-ray apparatus comprising, in combination, a table for receiving the patient thereon, a supporting base for said table, means carried by said base for supporting said table for tilting movement about a transverse axis movable with respect to said base, means for tilting said table about said axis from a substantially horizontal position, means cooperating with said supporting means to locate said table with the top thereof at a predetermined working height above the floor and with said axis at its lowermost position in said horizontal position of said table, and means responsive to operation of said tilting means for effecting raising of said axis simultaneously with tilting movement of said table away from the horizontal about said axis to provide additional clearance between the downwardly tilted end of said table and the floor in the resulting tilted position of said table.

8. X-ray apparatus comprising, in combination, a table for receiving the patient thereon, a supporting base for said table, means carried by said base for supporting said table for tilting movement about a transverse axis, cooperating means carried by said base and said table for tilting said table in both forward and backward directions about said axis from the horizontal, said tilting means including means for automatically raising said axis with respect to said base simultaneously with tilting movement of said table away from the horizontal in either of said directions and automatically lowering said axis simultaneously with tilting movement of said table towards the horizontal, and means automatically stopping motion of said table in horizontal position and at predetermined limits of tilting movement.

9. X-ray apparatus comprising, in combination, a table for receiving the patient thereon, a supporting base for said table, means forming a pivot for said table having the axis thereof transverse of said table, supporting members for said pivot means at either side of said table, means supporting said supporting members for movement in a substantially vertical plane with respect to said base to maintain said axis in substantially constant relation with said base longitudinally of said table, means for locating said table in horizontal position in response to movement of said pivot means to the lowermost position thereof, and means for causing said pivot means to travel vertically and simultaneously causing said table to tilt about said axis from said horizontal position.

10. X-ray apparatus comprising, in combination, a table for receiving the patient thereon, a supporting base for said table, means forming a pivot for said table having the axis thereof transverse of said table, means movable with respect to said base for guiding said pivot means for movement in a path directed upwardly with respect to said base, means on said base for supporting said table independently of said pivot means, and means cooperating with said supporting means to cause tilting movement of said table

12

and simultaneous upward movement of said pivot means as said table tilts away from a horizontal position and downward movement of said pivot means as said table tilts towards a horizontal position.

5 11. X-ray apparatus comprising, in combination, a table for receiving the patient thereon, a supporting base for said table, means forming a pivot for said table having its axis transverse of said table, means movable with respect to said base for guiding said pivot means in a path directed upwardly with respect to said base, cooperating means on said base and said table for supporting said table independently of said pivot means, and means for effecting relative movement of said cooperating means in an arc having a center spaced from the axis of said pivot means to effect simultaneous tilting movement of said table about said pivot means and linear movement of said pivot means along said path.

10 12. X-ray apparatus comprising, in combination, a table for receiving the patient thereon, a supporting base for said table, means for pivoting said table about a transverse axis, means carried by said base providing a mounting for said pivot, means movable vertically with respect to said base to raise and lower said axis, and means for applying a torque to said table at a point spaced below the lowest position of said pivot means to cause vertical movement of said pivot means and simultaneous tilting movement of said table about said axis.

15 13. X-ray apparatus comprising, in combination, a table for receiving the patient thereon, a supporting base for said table, means providing a pivotal mounting for said table, means supporting said pivot means on said base for upwardly directed movement with respect to said base, means for imparting upward movement to said pivot means to raise and lower said pivot and table, tracks carried by said table at positions spaced from said pivot means, and means for causing said tracks to pass through a predetermined position fixed with relation to said base as said pivot means moves up and down to effect tilting of said table about said pivotal mounting simultaneously with said movement of said pivot means.

20 14. X-ray apparatus comprising, in combination, a table for receiving the patient thereon, a supporting base for said table, means providing a pivotal mounting for said table, means supporting said pivot means on said base for movement in an upwardly directed path with respect to said base and constructed to position said pivot means at a reference position with respect to said base when said table is horizontal, drive means carried by said base, and means operatively connecting said drive means with said table at a position spaced from the axis of said pivotal mounting for causing said table to tilt about said pivotal mounting and simultaneously causing said pivot means to travel in said upwardly directed path to provide additional clearance below the downwardly tilted end of said table in the resulting tilted position of said table.

25 15. X-ray apparatus comprising, in combination, a table for receiving the patient thereon, a supporting base for said table, means for pivoting said table about a transverse axis, means carried by said base providing a mounting for said pivot means movable vertically with respect to said base, means for applying a torque to said table at points spaced below the lowest position of said pivot means to cause said pivot means to move vertically and said table to tilt about said

axis, said torque-applying means being constructed to apply torque selectively in either direction to the table, and switch means for controlling said torque-applying means and positioned to cooperate with control means carried by said table for automatically stopping said torque-applying means when said table is horizontal and when said table reaches predetermined limits of tilting motion in each direction from the horizontal.

16. X-ray apparatus comprising, in combination, a table for receiving the patient thereon, a base for said table, pivot means supporting said table for tilting movement about a horizontal transverse axis located intermediate the ends of said table and spaced from each end thereof by a distance greater than the height of said table from the floor when in horizontal position, means for supporting said pivot means for upwardly directed movement with respect to said base, means for locating said table in horizontal position in response to movement of said pivot means to its lowermost position, cooperating means carried by said table and said base for tilting said table about said axis and simultaneously raising said pivot means to provide clearance between the floor and the lower end of said table in tilted position in accordance with the angle of tilt thereof, and means for selectively operating said cooperating means to cause said table to tilt forwardly or rearwardly from the horizontal during upward movement of said pivot means.

17. X-ray apparatus comprising, in combination, a table for receiving the patient thereon, a base for said table, guide means, means supporting said guide means on said base for upwardly directed movement with respect to said base, means supporting said table on said guide means for tilting movement about a horizontal axis located intermediate the ends of said table and spaced from each end thereof by a distance greater than the height of said table from the floor when in horizontal position, a plurality of gear sectors secured to said table and forming a continuous curvilinear gear track, and means coaxial with said driving gear for maintaining said gear and said gear track in positive engagement to cause simultaneous tilting of said table about said axis and movement of said guide means with respect to said base sufficient to provide clearance between the floor and the lower end of said table in tilted position in accordance with the angle of tilt thereof.

18. X-ray apparatus comprising, in combination, a table having a top for receiving the patient thereon, a base for supporting said table on the floor, means forming a pivotal mounting for said table, means supporting said pivot means on said base for upwardly directed movement with respect to said base, means for positioning said pivot means at a reference position with respect

to said base when said table top is horizontal, the axis of said pivot being intermediate the ends of said table and spaced from the head end thereof by a distance greater than the height of said table top from the floor when said table is horizontal, cooperating drive means on said base and said table for causing said table top to tilt to a Trendelenburg position with said head end thereof of lowermost, and means responsive to operation of said drive means for simultaneously causing said pivot means to travel in said upwardly directed path above said reference position to provide clearance for receiving the head end of said table above the floor through a wide angular range of Trendelenburg positions.

19. X-ray apparatus comprising, in combination, a tiltable table having a top for receiving the patient thereon, a supporting base for said table, means forming a pivot for said table having the axis thereof transverse of said table, movable means supporting said pivot means for movement in a path directed upwardly with respect to said base, means for locating said table in horizontal position in response to movement of said pivot means to the lowermost position thereof, the axis of said pivot being intermediate the ends of said table and spaced from each end thereof by a distance greater than the height of said table top from the floor when said table is horizontal, drive means for causing said pivot means to travel upwardly from said lowermost position thereof to provide clearance for receiving the lower end of said table above the floor through a wide angular range of tilted positions, and cooperating means on said base and said table responsive to operation of said drive means for causing said table to tilt about said pivot axis simultaneously with said travel of said pivot means.
